WHEEL

Millard Fillmore Harty, Jr., Bloomfield Hills, Mich.,
assignor to Motor Wheel Corporation, Lansing, Mich.

Filed Oct. 1, 1970, Ser. No. 25,286

Term of patent 14 years

Int. Cl. D12—16

U.S. Cl. D14—30

FIG. 1 is a perspective view of a wheel as viewed at an angle to the outboard face of the wheel showing my new design.

FIG. 2 is a front elevational view of the wheel of FIG. 1 also looking at the outboard face thereof.

FIG. 3 is a vertical sectional view taken on the line 3—3 of FIG. 2.

FIG. 4 is a circumferential and axial sectional view taken on the line 4—4 of FIG. 2.

FIG. 5 is a circumferential and axial sectional view taken on the line 5—5 of FIG. 2.

I claim:

The ornamental design for a wheel, substantially as shown and described.
